UNITED STATES PATENT OFFICE

BEN A. BALL, OF PAWTUCKET, RHODE ISLAND, ASSIGNOR TO AMERICAN TEXTILE COMPANY, INC., OF PAWTUCKET, RHODE ISLAND, A CORPORATION OF RHODE ISLAND

DESIGN FOR LACE

Application filed January 22, 1930. Serial No. 34,233. Term of patent 7 years.

To all whom it may concern:

Be it known that I, BEN A. BALL, a citizen of the United States, and a resident of Pawtucket, in the County of Providence and State of Rhode Island, have invented the new, original, and ornamental Design for Lace, of which the following is a specification.

Reference is had to the accompanying drawing, in which—

The figure is an elevation of lace, showing my new design, a repeat unit of which is contained between the horizontal dot and dash lines and the vertical marginal edges. This unit of the design is repeated in the relation shown.

I claim:

The ornamental design for lace, substantially as shown and described.
